DISTRIBUTING VALVE

James D. Robinson, Memphis, Tenn.

Application March 22, 1950, Serial No. 151,289

12 Claims. (Cl. 137—463)

1

This invention relates to rotary valves and, more particularly, to a valve for distributing liquid from an inlet to any one of a plurality of outlets.

The object of the invention is to provide a rotary valve responsive to the flow, or the pressure resulting from the flow, of liquid through it for directing liquid to certain outlets so long as the liquid flowing therethrough sustains a pre-determined volume and, when the volume drops below the critical value, to switch the flow then to a neutral or normal outlet. This arrangement was engendered for dishwashing apparatus embodying three sinks respectively for water treated with detergent solution, clear water, and water treated with a strong germicide, such as chlorine solution. In this system water leaving the distributing valve towards the detergent sink is passed through a treating valve from which it takes off detergent concentrate. So long as the volume of flow through the treating valve exceeds a pre-determined value, the water delivered to the detergent sink has in it the correct proportion of detergent solution, but should the volume of flow through the treating valve drop below the pre-determined value, less detergent might be taken off and, consequently, the solution delivered to the sink would be too weak. The same applies to the germicidal side of the system. It is intended now to provide a three-way switch valve having an input connectable to the ordinary fresh water tap so that when the water passes through, it will be normally directed through a central or neutral outlet which, in the system for which the valve was devised, leads to the fresh water sink. The operator may switch the valve to direct the water to either one of the side outlets, and the valve will remain so switched so long as the water flow is sustained at the desired level. However, should the water flow drop for any reason, as by decreased pressure in the supply line, the valve will switch the flow back to the central or neutral outlet.

More specifically, it is intended by this invention to provide a rotary valve having a chamber wherein the back pressure of water flowing through is utilized to hold the valve in any one of its non-neutral positions, and wherein the reactive forces resulting from back pressure are always opposed by forces exerted by a centering mechanism tending always to return the valve to its neutral position. When the back-pressure forces become insufficient to hold the valve in non-neutral position the centering forces be-

2

come dominant to return the valves to neutral position. It is particularly intended to render less critical the resolution of forces which tend, on the one hand, to hold the valve in non-neutral position and, on the other hand, to return it to neutral position, by the addition of a positive kick-off opposing the back pressure forces in the valve chamber so that if the valve is in a non-neutral position and the back pressure in the valve chamber drops below a critical value, the kick-off will relieve the back-pressure water directly from the valve chamber to the neutral outlet, thereby substantially eliminating the forces resulting from back pressure which tend to hold the valve in non-neutral position and, of course, allowing the centering forces overwhelmingly to dominate. In the execution of these specific objects it is intended to provide a valve chamber having three angularly spaced outlet ports and a common inlet port, and a valve rotor having a main channel which normally directs liquid from the common inlet port to the central outlet port when centered by a mechanism carried by the rotor and, ball valves in angularly spaced sockets so that the outlet ports are closed except for the one with which the main channel is in registry. In addition, it is proposed now to provide alcove passages from the main channel of the rotor to the back sides of the ball sockets so that the back pressures of water from the central channel pushes from behind on the ball valves so as to assist in the seating the ball valves closed against seats in the non-selected outlet ports, thereby not only sealing off the non-selected ports, but also preventing the centering mechanism from returning the rotor to its neutral position. It is thus apparent that a spring pressed kick-off plunger in the central or neutral outlet port operates against a ball closing that port and against the forces, including the water back pressure force, which seat the ball. Therefore, if the back pressure force drops below the critical value, the plunger will crack the ball off its seat, thereby exhausting the water under back pressure from behind the ball through the crack so as to eliminate the back pressure forces as holding factors. Still another object is to provide a distributing valve which, of practical necessity, embodies a plurality of springs, such as in a centering mechanism and in ball biases operating in opposition to volumetric forces, but to establish the criterion of the balance between volumetric and spring forces by means of single spring, or kick-off device which can be easily and quickly replaced

by another of different strength. In the application of the distributing valve to the system for which it was devised, the maximum strength of the treated water solution in the side tubs can be increased or decreased simply by replacing the kick-off mechanism with one having a weaker or stronger spring. It is unnecessary to open up the valve and adjust or replace the springs in the centering mechanism or the springs which bias certain of the balls closed.

These and other objects will be apparent in the following specification and drawings, in which:

Fig. 1 is a vertical cross section taken with the valve in neutral position along the line 1—1 of Figs. 5 and 8;

Fig. 2 is a plan view of the valve casing with the rotor, centering mechanism and top removed;

Fig. 3 is a side elevation of the rotor, a rotor shaft and handle;

Fig. 4 is a bottom plan view showing the underside of the rotor;

Fig. 5 is a horizontal section taken along the line 5—5 of Fig. 1 through the casing and rotor looking downwardly in the direction of the arrows;

Fig. 6 is a horizontal section along the line 6—6 of Fig. 1 looking downwardly in the direction of the arrows and showing a plan of the centering mechanism in neutral position;

Fig. 7 is an exploded view showing, in perspective, the moving parts of the centering mechanism;

Fig. 8 is a diagrammatic cross section of the valve taken along the lines 8—8 of Fig. 5 showing the application of the forces holding the valve in neutral or center position;

Fig. 9 is a view similar to Fig. 8 but showing the valve turned to direct liquid through the right-hand non-neutral outlet and diagrammatically illustrating the dominating forces tending to hold the valve in non-neutral position;

Fig. 10 is a diagrammatic plan view of the centering mechanism operating under the conditions of Fig. 9 and tending unsuccessfully to return the valve to the neutral position of Fig. 8; and

Fig. 11 is a view similar to Fig. 9 but illustrating the force conditions prevailing when flow through the valve drops below a pre-determined critical value and instantaneously prior to return of the valve to the neutral position of Figs. 1, 5, 6 and 8.

General operation

Referring now to the drawings in which like reference numerals denote similar elements, the rotary valve includes a casing 2 best shown in Figs. 1, 2, 5, 8, 9 and 11. Casing 2 is formed with a base 4 and a hollow cylindrical chamber shell 6 closed by a top 8 engaged in threads 10 around the upper interior of shell 6. In the back end of base 4 is a downwardly facing main inlet 12 threaded at 13 for connection with a suitable source of liquid, such as the water supply pipe of a sink. Angularly spaced about the exterior of base 4 are three outlets 14, 16 and 18 respectively. Hereinafter, outlet 16 will be considered the neutral outlet, while outlets 14 and 18 will be termed non-neutral. At the top of the valve there is a handle 20 for rotating the mechanism described herein below. For purposes of illustrating one important application of the invention it will be assumed that outlet 14 is connected

so as to pass water through a detergent mixing valve, outlet 16 is to pass clear water directly to the point of utilization, and outlet 18 is to pass water through a chlorinating valve. When in neutral position the valve emits water from main inlet 12 through central outlet 16, and when turned to either of its non-neutral positions the valve emits water through the selected non-neutral outlet 14 or 18 and will continue to do so, even without manual holding, so long as the flow therethrough sustains the necessary volume. If the volume drops below a critical volume the valve will automatically return to its central position wherein flow re-establishes through neutral outlet 16.

The casing

In base 4 of casing 2 there is an inlet channel 21 connecting main inlet 12 with an inlet port 22 centrally disposed in the upper face 29 of base 4 at the bottom of the valve chamber. Angularly disposed in base face 29 are three outlet ports 24, 26, and 28, in each of which are disposed valve seats 30, preferably formed of "neoprene," or similar composition well known in the valve seat art, flush mounted in seat recesses 32. Outlet ports 24, 26 and 28 respectively constitute inner termini of outlet channels 34, 36 and 38 connecting them respectively with outlets 14, 16 and 18.

The rotor

Snugly but rotatably nesting in the lower portion of chamber shell 6 is valve rotor 40 detailed in Figs. 3 and 4, on the upper center of which is affixed shaft 42 passing upwardly through sleeve bearing 43 in casing top 8 and non-rotatably connected at 44 to the inner end of handle 20. In the lower face of rotor 40 is a main channel 46 with an inner end lying over and in communication with the inlet port 22 in all angular positions of the valve, it being apparent that when rotor 40 is positioned centrally as in Figs. 1, 5 and 8, main channel 46 establishes communication between inlet port 22 and outlet port 26, but when turned clockwise or counter-clockwise, main channel 46 establishes communication between inlet port 22 and either of outlet ports 24 or 28.

The centering mechanism

Rotor 40 is normally biased to its central or neutral position; wherein channel 46 connects inlet and outlet ports 22 and 26 respectively, by the centering mechanism detailed in Figs. 1, 6, 7 and 10 and indicated generally at 48. Centering mechanism 48 consists of two identical arcuate centering members 50 and 52, each having an arcuate outer rib 54 terminating in end faces 56 and 56' and having, on one side, a web-like arcuate plate 58 having at its center a sleeve-like boss 60 surrounding a center hole 62. Bosses 60 serve as spacers, and bearings so that the members 50 and 52 rotate freely about shaft 42. A torque spring 64 is contained between members 50, 52 normally in slightly wound condition with its ends 66 engaged in holes 68 in end faces 56'. In Figs. 6 and 10 it is apparent that in all angular positions of the valve, at least one of end faces 56 abuts the inner end of an abutment screw 70 affixed through the upper portion of chamber shell 6 and, further, that at least one of end faces 56 always engages the upstanding abutment post 72 affixed in the top of valve rotor 40. If rotor 40 is turned counterclockwise from the central

position, centering mechanism 48 exerts a torsional force designated F4 in Figs. 9, 10 and 11, tending always to return the rotor to its central position. This will be understood from the diagram of Fig. 10 which shows when the abutment post 72 was turned with the rotor 40 from its dotted line to its full line position, torque spring 64 was wound by the counterclockwise movement of arcuate member 52 which, of course, was driven by abutment post 72. The other centering member 50 would not follow this movement because of the engagement of its end 56 against abutment screw 70. Accordingly there resulted a torsional force, indicated by the arrow of line F4, exerted against abutment posts 72, thereby tending to return the rotor 40 to its central position. Obviously a corresponding return torque would be exerted on rotor 40 if it were turned so as to bring main channel 46 in registry with outlet port 24. In either of the extreme non-neutral positions of the centering mechanism, the end faces 56 engage one another so as to stop the rotor with its main channel over the selected one of outlet ports 24 or 28.

The ball valves

The mechanism for sealing off the inactive outlet ports and for holding rotor 40 in non-neutral position includes, on one side of passage 46, a ball socket 74 communicating with passage 46 through an alcove passage 76. On the opposite side of channel 46 there is a similar ball socket 78 also connected with channel 46 through and alcove passage 80. In each of ball sockets 74 and 78 are compression springs 82 and 83. Spring 82 exerts a downward force F3 on a ball 84 which is prevented from complete expulsion from its socket 74 by a capture lip 86, while spring 83 exerts a similar downward force F3 on ball 88 in socket 78, this latter ball also being held against complete expulsion by a capture lip 89. Capture lips 86 and 89 are active when the rotor is removed as shown in Fig. 3. Extending backwardly, as seen in Figs. 1, 3, 4, 5 and 9 from socket 74 is a further alcove passage 90, and another alcove passage 92 similarly extends back from ball socket 78. Alcove passage 90 transmits fluid under pressure to the back side of a free ball 94 sliding vertically in socket 96 while back alcove passage 92 similarly terminates in socket 100 behind free ball 98.

When the valve is in its neutral position of Figs. 1, 5 and 8, balls 84 and 88 rest in seats 30 so as to close ports 24 and 28 in the inner ends of outlet passages 34 and 38, these balls being firmly seated by forces F2 exerted downwardly by springs 82 and 83. There is an additional force exerted downwardly on balls 84 and 88 which results from the back pressure of water flowing in the rotor 40. The stream of water flowing through inlet port 22 and main channel 46 exerts a primary force in the direction of its flow diagrammatically indicated at F1. As this main stream of water traverses main channel 46, back pressure or reactive forces F1' are transmitted through the various alcove passages 76 and 90, on the one side, and 80 and 92 on the other side, thereby applying downward forces F1' on all the balls. These balls 94 and 98 and the back pressure or reactive forces F1' do not become of particular importance until rotor 40 is turned from its neutral position. Then, when rotor 40 is turned so as to bring main channel 46 in communication with one of the non-neutral outlets, such as through outlet port 28, ball 84 is moved

over to close the central outlet port 26 while ball 94, hitherto inactive, is moved over to close outlet port 24. In the position shown in Fig. 9 the downward force F2 exerted by spring 82 on ball 84 assists in sealing the ball against its seat in outlet port 26 and, in addition, the sidewise engagement of ball 84 against its seat tends to block return movement of rotor 40 against the torque force F4 exerted by wound torque spring 64 in centering mechanism 48. However, the blocking force resulting alone from the downward force F2 of spring 82 on ball 84 would, in and of itself, be insufficient to combat the return torque force F4 exerted by wound spring 64. When there is no water flowing through the valve, rotor 40 will not stay over by itself in either of the non-neutral positions. The resulting forces which establish the overbalance sufficient to overcome the return torque force F4 are from the back pressure reactive forces F1' exerted downwardly on balls 84 and 94 (Fig. 9). Thus, forces F2 plus forces F1' exerted on ball 84, plus F1' on ball 94 effect blocking of both balls against the sides of the seats in outlet ports 24 and 26, and so long as the volume of flow through the valve is sufficiently high to maintain primary force F1 above a predetermined value, the reactive or back pressure forces of F1' will be sufficient to block balls 92 and 94 against their seats and thus prevent return of rotor 40 to its neutral position. However, when the flow of water decreases below the desired volume, the total of the resulting back pressure forces F1', together with compression spring force F2, becomes insufficient to block balls 84 and 94 against the thrust from return torque F4.

The kick-off

The kick-off is provided to render less critical the selection and tensioning of torque spring 64 in centering mechanism 48 and compression springs 82 and 83 on balls 84 and 88, respectively, and also to provide for easy variation of the volume of water required to hold the valve over in either of its non-neutral positions. In a threaded recess 102 at the bottom end of outlet passage 36 engages a threaded hollow plug 104 slidably supporting an upwardly extending plunger 106 biased upwardly by a compression spring 10. Spring 108 bears against an enlargement 110 on the bottom end of plunger 106 sliding in a sleeve 112 in the upper portion of the plunger. When plunger 106 is fully extended, its upper end lies in the plane of the top of outlet port 26, but when depressed, it transmits an upward force F3 from compressed spring 108. In Fig. 11 it is apparent that when plunger 106 is extended a ball which otherwise would be seated in outlet port 26 is cracked upwardly, the force F3 of spring 108 being greater than the force F2 of spring 82, but less than the total of force F2 plus F1' resulting from the desired sufficiency of water flowing through the valve. Thus, when force F' decreases the ball is cracked upwardly, most of the back pressure or reactive forces F1' are released by the flow of back water through the crack and out of the valve via port 26, outlet passage 36, and outlet 16, thereby effectively eliminating back pressure or reactive forces F1' as factors which hitherto resulted in the blocking of balls 84 and 94, against their seats and, in turn, permitting return torque F4 of centering mechanism 48 to dominate by camming balls 84 and 94 off their seats. This removes the blocking of rotor

40 and allows it to return under torque F4 to its central position.

While only one of the non-neutral positions and actions of the valve have been described in the foregoing, it is obvious that a similar sequence occurs when handle 20 is turned clockwise so as to register main channel 46 with outlet port 24. It is likewise apparent that the specific arrangement of the various ports, passages and channels may partake of various form, and that the balance of the forces operating within the valve can easily be altered by the adjustment or replacement of the various springs, particularly spring 108, or, preferably by substitution of a new plunger assembly 104, 106, etc., so as to vary the volume of water required to hold the valve over to either of its non-neutral positions. The invention detailed above is not limited to the specific apparatus and, of course, is adaptable to many systems other than the one for which it was described, and is intended to cover all modifications, substitutions, and equivalents within the scope of the following claims.

I claim:

1. A rotary valve comprising a casing defining a cylindrical chamber with a substantially flat bottom wall, an inlet port centrally disposed in said bottom wall, first, second and third outlet ports disposed radially from said inlet port at equal angular intervals in said bottom wall, a rotor rotatably disposed in said chamber and having a substantially flat bottom face engaged against the bottom wall of said chamber, a main channel in the bottom face of said rotor extending radially from the center towards the periphery thereof so as to register constantly with said inlet port and selectively with said outlet ports, said rotor having first and second ball sockets extending upwardly from the bottom face and respectively displaced on each side of said main channel at angular intervals corresponding to the angular spacing between said outlet ports, and third and fourth ball sockets extending upwardly in said rotor from said bottom face and respectively disposed at said angular intervals from said first and second sockets, balls in said sockets dimensioned for seating engagement with said ports so as to close the same upon registry therewith, said rotor having alcove channels connecting said main channel with said ball sockets whereby to transmit back-pressure forces on said balls, and a centering mechanism connected between said chamber and said rotor normally biasing said rotor to a neutral position in which said main channel registers with said second outlet port.

2. The combination claimed in claim 1, and springs in said first and second sockets exerting a downward force thereon.

3. The combination claimed in claim 1, and a spring-pressed plunger in said second outlet port arranged to exert an upward force against a ball registering therewith, said upward force being greater than the downward force exerted by either of the springs in said sockets.

4. A rotary valve comprising a hollow cylindrical casing having a common inlet port, a neutral outlet port, and first and second non-neutral outlet ports equi-angularly disposed on each side of said neutral outlet port, a rotor in said casing, said rotor having a main channel arranged to register with said common inlet port in all rotational positions and having a neutral position in which said main channel connects

said common inlet port and said neutral outlet port, said rotor being selectively rotatable from said neutral position to either of first and second non-neutral positions in which said main channel connects said common inlet port and the selected one of said non-neutral outlet ports, a centering mechanism including spring means oppositely engaged between said rotor and an abutment in said casing for exerting a return torque force on said rotor biasing the same from said non-neutral positions to said neutral position, first and second ball sockets in said rotor angularly spaced on opposite sides of said main channel, said sockets respectively registering with said first and second non-neutral outlet ports when said rotor is in said neutral position and alternately registering with said neutral outlet port when said rotor is turned to said non-neutral positions, third and fourth ball sockets extending upwardly in said rotor from said bottom face and spaced from said first and second sockets so as to register respectively with said first and second outlet ports when said first and second sockets register with said neutral outlet port, ball valves in each of said sockets dimensioned to seat in said outlet ports for closing the same upon registry therewith, and channel means in said rotor connecting said main channel and said ball sockets for transmitting fluid under back pressure resulting from flow of fluid in said main channel to said balls, whereby to seat the same tightly in said outlet ports and for blocking said rotor against the return torque of said centering mechanism.

5. In a device of the type described, a chamber member having an inlet and a plurality of outlets spaced from one another, a valve member movably mounted in said chamber member and having a passage therethrough, said valve member being movable from a predetermined selected position to an alternate selected position whereby to bring one end of said passage selectively into registry with said outlets, the other end of said passage being in registry with said inlet in all of said selected positions of said valve member, bias means for biasing said valve member to said predetermined selected position which said passage registers with a certain one of said outlets, holding means engaging between said chamber and valve members and responsive to the pressure of fluid flowing through said passage for holding said valve member in said selected alternate position against the action of said bias means.

6. In a device of the type described, a chamber member having an inlet and a plurality of outlets, a valve member movably disposed in said chamber member and having a passage therethrough, said passage being in constant registry with said inlet, said valve member being movable from a predetermined selected position to an alternate selected position whereby said passage connects said inlet selectively with said outlets, bias means engaged between said members for biasing said valve member to said predetermined selected position in which said passage connects said inlet and a certain one of said outlets, closure means in said valve member engageable in said outlets and responsive to the pressure of fluid in said passage for closing all said outlets other than the selected one with which said passage connects and for holding said valve in selected position, and disabling means in said chamber member inversely responsive to said pressure for disengaging said

closure means from at least one of said outlets when said pressure is less than a predetermined value.

7. In a device of the type described, a chamber member having an inlet and a plurality of outlets extending externally from said chamber member, valve seats at the inner ends of said outlets, a valve member having a main passage therethrough, said valve member being movable in said chamber member from a predetermined neutral position to a plurality of alternate positions in which said main passage selectively connects said inlet with said outlets, bias means engaged between said members for exerting a bias force against said valve member to said neutral position in which said inlet is connected through said main passage to a certain one of said outlets, ball valves and sockets therefor in said valve member spaced from said main passage, said sockets being disposed with respect to said valve seats so that said ball valves close against the valve seats in the outlets other than the one with which said main passage connects, said ball valves, when closed against said valve seats being engaged between the walls of said sockets and the sides of said valve seats thereby tending to block said valve member against the bias force, and conduit means in said valve member connecting said main channel and said ball valve sockets thereby transmitting fluid under pressure from said main channel, whereby to exert closing and blocking forces against the ball valves.

8. The combination claimed in claim 7, and spring means in at least some of said ball sockets engaged between said valve member and said balls and exerting closing and blocking forces thereon.

9. The combination claimed in claim 7, and spring means in one of said outlets arranged to exert a cracking force against a ball closed thereagainst.

10. In the combination claimed in claim 7, first spring means in at least some of said ball sockets engaged between said balls and said valve member, and second spring means in one of said outlets arranged to exert a cracking force against a ball closed thereagainst, said second spring means being effectively stronger than the first.

11. A rotary valve having a hollow casing with an inlet port and at least two outlet ports respectively disposed in first and second angularly spaced positions, a rotor angularly movable in

said casing and having a main channel registering in all operative positions with said inlet port and respectively registering with said outlet ports upon angular movement of said rotor between a neutral position and an alternate position whereby to establish communication between said inlet port selectively with either of said outlet ports, means for exerting a biasing force on said rotor tending to move the same angularly to said neutral position whereby to maintain the channel normally in registry with one of said outlet ports, valve means in said rotor for closing the non-selected outlet port while said main channel establishes communication between said inlet and the selected one of said outlet ports, and conduit means connecting said main channel and said valve means for exerting a closing force on the latter resulting from back pressure of flow through said main channel.

12. In a control valve including a chamber member having an inlet and a plurality of outlets, a movable valve member having a passage therein, said valve member being movable between a predetermined neutral position and plurality of alternate positions whereby to connect said inlet via said passage with selectively said outlets, the improvement which comprises, yieldable means engaged between said members and biasing said valve member towards said neutral position, valve means in one of said members operable in response to the positioning of said valve member for closing all said outlets other than the selected one, holding means responsive to the fluid flowing through said control valve for exerting a holding force on said valve member substantially proportioned to the pressure of said fluid in said valve, and means of predetermined force in said control valve operating in opposition to said holding force for disabling said holding means upon dropping of said fluid pressure below a predetermined value.
